SPOOL FOR RIBBONS AND OTHER
NARROW FABRICSBertram J. Goldsmith, New York, N. Y., assignor
to General Ribbon Mills, Inc., New York, N. Y.,
a corporation of Pennsylvania

Application May 8, 1936, Serial No. 78,562

12 Claims. (Cl. 206—51)

The present invention relates to spools and, in its more specific aspects, is concerned with spools for carrying rolls of narrow fabrics such as ribbons, bands, tapes, etc. The invention is also concerned with a novel method of mounting rolls of material on packaging spools.

Narrow fabrics such as ribbons, tapes, etc., are usually wound on pre-formed spools having cylindrical cores, and ribbon manufacturers are required to keep in stock large quantities of such spools. As the necessary stock of spools takes up a lot of room, pre-formed spools are for that reason, among other things, undesirable. It is therefore an object of this invention to obviate the necessity for the manufacturer to keep in stock preformed spools and, for that purpose, to provide spools which can be readily formed from blanks of sheet material, large quantities of which may be kept in a relatively small space and made up into the spools as needed.

Another object of the present invention is to provide a spool of such construction that it can be formed from sheet material by simple mechanical operations such as cutting and folding.

A further object of the invention is to provide an improved method of mounting rolls of ribbons, tapes and other narrow fabrics on packaging spools.

A further object of the invention is to provide a spool of improved appearance whereby to enhance the ornamental appearance of the ribbon roll or package, and thus favorably impress the prospective purchaser and promote the sale of the ribbon.

A yet further object of the invention is generally to provide narrow-fabric or other spools which are simple in construction and which can be produced at low cost.

The above objects of the invention and other objects ancillary thereto will best be understood from the following description considered with reference to the accompanying drawing forming a part of the present specification.

In the drawing:

Fig. 1 is a perspective view of a spool embodying the present invention;

Fig. 2 is a plan view of a blank of sheet material from which the spool shown in Fig. 1 is formed;

Fig. 3 is a sectional view on the line 3—3 of Fig. 1;

Fig. 4 is a perspective view of a spool having a roll of ribbon wound thereon;

Fig. 5 is a view similar to Fig. 1, showing a modification;

Fig. 6 is a perspective view, on a reduced scale, of a roll of ribbon mounted on a temporary carrier, and illustrates one step in the present method;

Fig. 7 is a view similar to Fig. 4, illustrating a further form of the invention, and another step in the present method;

Fig. 8 is a perspective view of a member utilized in connection with the spool construction of Fig. 5.

Referring to the drawing in detail, the spool 10, illustrated in Fig. 1, is formed from the blank 12 illustrated in Fig. 2. Said blank may be made from any suitable sheet material such as cardboard, fibre-board, stiffened fabric, or thin bendable metal, although for the purposes of the present invention and especially in order to keep down the cost of the spools, said blank is made preferably of cardboard.

As here shown, the blank 12 is generally circular in peripheral outline and has a central opening 14 of octagonal outline defined by the inner edges 16 of the rectangular sections 18. Said sections 18 are defined by scoring said blank along spaced lines 20, extending outwardly at right angles from the inner edges 16 and constituting fold lines for forming the spool 10 from the blank. Said fold lines 20 are arranged in pairs, the lines of each pair being disposed in diverging relation and extending from the meeting ends of adjacent edges 16 to the outer periphery of the blank beyond the outer edges 19 of the rectangular sections 18, thereby defining together with an arcuate circumferential edge 22 a section 24 which is in the form of a sector of a circle, or substantially in the form of a triangle. Thus, the blank 12 comprises alternate rectangular and substantially triangular sections 18 and 24, respectively, disposed circumferentially of the blank about the central opening 14. Said blanks may be produced in large quantities by die-cutting the same from the sheet material.

In forming the spool 10 from the blank 12, the latter is folded along pairs of fold lines 20 alternately in opposite directions, forming substantially triangular side-wall portions 30 and 32 at opposite sides, respectively, of the spool, providing the spool flanges and intermediate wall portions 34 formed from the rectangular sections 18, providing the spool barrel. Said intermediate wall portions are disposed axially of the spool between the sides of the latter and are arranged in pairs extending radially in V-configuration. When the blank is thus formed into the spool, the

outer edges 35 of the intermediate wall portions 34 are spaced circumferentially of the spool and constitute the support or barrel for the ribbon R wound thereon, and the inner edges 36 of said intermediate wall portions 34 meet centrally of the spool and extend along a line axially thereof between opposite sides of the spool. The edge portions 31 of the side wall sections 30 extend radially beyond the edges 35 of the intermediate wall portion 34, forming flanges for retaining the roll of ribbon on the spool between the sides of the latter.

Instead of winding the ribbon directly in contact with the edges 35, an annular band 38 of paper or other suitable material may first be secured circumferentially of the spool in engagement with said edges, thereby holding the folded blank in the spool formation. This alternative construction is illustrated in Fig. 5.

In the form of the invention illustrated in Figs. 6 to 8, and in accordance with the present method of mounting rolls of ribbon on the spools, there is utilized a spool 10, but instead of winding the web of ribbon directly on the spool, said web is first wound into a roll Ra on a temporary carrier such as a cylindrical spool or mandrel 39 of any suitable form, after which said roll is removed from the temporary spool and mounted on the spool 10. While I have illustrated a single roll mounted on the temporary carrier therefor, it will be understood that in practice a relatively large number of said rolls may be wound on a single spool of suitable length, being disposed axially of said spool and readily removable therefrom for mounting on individual packaging spools 10. In order to permit the wound roll to be placed on the spool 10, the temporary spool or mandrel 39 is of such size as to provide a central opening in the roll Ra large enough to enable said roll to be slipped over the flanged ends 31 of the spool when the spool is in contracted condition with the inner edges 36 thereof in engagement with each other. After the wound roll has been placed upon the spool, a cylindrical block or expander member 40 of wood or other suitable material is inserted between said edges 36, thereby expanding the spool and forcing the edges 35 of the intermediate wall portions 34 of the spool into engagement with the inner convolution of the roll of ribbon.

It will be understood that the roll of ribbon may be wound on the spool 10 together with a protective paper strip disposed between ribbon convolutions, or when the roll is first wound and subsequently mounted upon the spool 10, said protective paper strip may be wound together with the ribbon on the temporary spool or mandrel 39.

While I have shown and described several of the preferred embodiments of my novel spool construction and the method of packaging rolls of ribbon in accordance with the present invention, it will be understood that the invention is capable of other embodiments than those herein shown or described and that each of the embodiments herein disclosed may vary as to details of construction and arrangements of parts. Therefore, I do not wish to be limited precisely to the present disclosure or to any part thereof, except as may be required by the appended claims considered with reference to the prior art.

Having thus described my invention, what I desire to claim and secure by Letters Patent of the United States is:

75 1. A spool made of sheet material and com-

prising flat side-wall portions at opposite sides of the spool, said portions being spaced from each other at each side of the spool and the portions at one side of the spool being circumferentially offset from the portions at the other side of the spool, and intermediate portions extending radially of the spool and laterally of the latter between the opposite sides thereof, the outer ends of said intermediate portions being spaced circumferentially of the spool and constituting the support for the web wound on the spool.

2. A spool made of sheet material and comprising flat side-wall portions at opposite sides of the spool, said portions being spaced from each other at each side of the spool and the portions at one side of the spool being circumferentially offset from the portions at the other side of the spool, and intermediate portions extending radially of the spool and laterally of the latter between the opposite sides thereof, the outer ends of said intermediate portions being spaced circumferentially of the spool and constituting the support for the web wound on the spool, a plurality of said side-wall portions extending outwardly beyond said outer ends of the intermediate sections thereby forming flanges for retaining the web on said support between the sides of the spool.

3. A spool made of sheet material and comprising flat side-wall portions at opposite sides of the spool and integral intermediate portions extending radially of the spool and laterally of the latter between the opposite sides thereof, and a member engageable with the inner ends of said wall portions for holding said ends spaced from the center of the spool.

4. A spool comprising side-wall portions having side edges extending in divergent relation from the center of the spool toward the periphery thereof, intermediate portions integral with said side-wall portions and extending laterally of the spool between the sides thereof, and a member engageable with the inner ends of said wall portions for holding said ends spaced from the center of the spool.

5. A spool comprising side-wall portions having side edges extending in divergent relation from the center of the spool to the periphery thereof, intermediate portions connected to said side-wall portions and extending laterally of the spool between the sides thereof, said intermediate portions being arranged in pairs extending radially of the spool in V-configuration, and a member engageable with the inner ends of said wall portions for holding said ends spaced from the center of the spool.

6. A spool blank comprising a sheet of foldable material having a central opening and wall-forming portions disposed about said opening and comprising alternately arranged substantially triangular and rectangular sections defined by pairs of fold lines extending in diverging relation from said opening toward the periphery of the blank.

7. A spool blank comprising a sheet of foldable material having a central opening and wall-forming portions disposed about said opening and comprising alternately arranged substantially triangular and rectangular sections defined by pairs of fold lines extending in diverging relation from said opening toward the periphery of the blank, the outer edges of said triangular sections being further from said opening than the outer edges of said rectangular sections.

8. A spool comprising a blank of sheet material

having a central opening and foldable along spaced pairs of lines extending in diverging relation from said opening toward the blank periphery, the portions of the blank between alternate pairs of fold lines being folded in opposite directions and positioned at opposite sides of the spool and extending radially thereof, and the portions of the blank between successive lines of different pairs of fold lines being disposed axially of the spool and extending radially thereof.

9. A spool comprising a blank of sheet material having a central opening and folded along spaced pairs of lines extending in diverging relation from said opening toward the blank periphery, the portions of the blank between alternate pairs of fold lines being folded in opposite directions and positioned at opposite sides of the spool and extending radially thereof, the portions of the blank between successive lines of different pairs of fold lines being disposed axially of the spool and extending radially thereof, and means for securing said blank in folded spool formation.

10. A spool comprising a blank of sheet material having a central opening and folded along spaced pairs of lines extending in diverging relation from said opening toward the blank periphery, the portions of the blank between alternate pairs of fold lines being folded in opposite direc-

tions and positioned at opposite sides of the spool and extending radially thereof, the portions of the blank between successive lines of different pairs of fold lines being disposed axially of the spool and extending radially thereof, and a strip of material disposed circumferentially of the spool in engagement with peripheral portions of the spool for holding the blank in said folded relation.

11. A spool comprising flat side wall portions extending perpendicular to the axis of the spool and forming the side flanges therefor, and portions extending parallel to the axis of the spool and forming a barrel therefor, the said perpendicularly disposed portions being integral with said barrel-forming portions, said flat side wall portions extending beyond said barrel of the spool.

12. A spool formed from sheet material and comprising flat side wall portions extending perpendicular to the axis of the spool and forming the side flanges therefor, and folded portions extending parallel to the axis of the spool and forming a barrel therefor, the said perpendicularly disposed portions being integral with said barrel-forming portions, said flat side wall portions extending beyond said barrel of the spool.
